INVENTOR
CHARLES G. CALLAN.

BY *Feeherty & Co. Ltd.* F.M.S.

UNITED STATES PATENT OFFICE.

CHARLES GEORGE CALLAN, OF BENGOUGH, SASKATCHEWAN, CANADA.

WINDOW-SASH LOCK.

Application filed June 5, 1920, Serial No. 386,776. Renewed October 24, 1922. Serial No. 596,684.

To all whom it may concern:

Be it known that I, CHARLES GEORGE CALLAN, a subject of the King of Great Britain, a resident of the town of Bengough, Province of Saskatchewan, Dominion of Canada, have invented certain new and useful Improvements in Window-Sash Locks, of which the following is a specification.

10 This invention relates to improvements in window sash locks, and the objects of the invention are to provide means whereby the sash may be locked in any elevated position, to permit of the device being mounted 15 on window frames at present in use, to facilitate securing the lock in unlocked position so that the sash may be freely elevated and lowered when desired, to simplify the construction of the lock and cheapen the 20 cost of manufacture, and generally to adapt the lock to better perform the functions required of it.

With the above and other objects in view, the invention consists essentially of the 25 proved construction particularly described and set forth in the following specification and accompanying drawings forming part of the same.

In the drawings:

30 Figure 1 is a fragmentary perspective view of a side member of a window frame showing the improved sash lock mounted thereon.

Figure 2 is a vertical section through the 35 side member of the window frame, showing the sash lock in position, with the lock unlocked.

Figure 3 is a longitudinal section of the 40 side member of the window frame, showing the improved sash lock in locked position.

Figure 4 is a perspective view of the improved sash lock.

Figure 5 is a longitudinal section of the 45 improved sash lock.

Like characters of reference refer to like parts in the several figures.

50 Referring to the drawings; A represents the side member of a window frame provided with a parting strip 10, and an inner strip 11, which is provided intermediate of its length with a recess 12.

The lock B which forms the subject matter of the present invention is secured to

the member A between the parting strip 55 10 and the inner strip 11, and comprises a U-shaped member 13, the arms 14 and 15 of which are unequal length, and this U-shaped member is secured to the window frame by screws or the like. 60

The arms 14 and 15 are provided with orifices 16 therein arranged in alignment, and a locking member 17 consisting of an angle shaped rod of rectangular cross section has one arm journaled in the orifices 65 16. The other arm of the locking member is provided with a sleeve 18 slideable thereon and carrying a tongue 19, and this arm of the locking member 17 and the tongue 19 embraces the arm 15 of the U-shaped 70 member 13 therebetween.

The locking member 17 is thus held in a locked or unlocked position by means of the tongue 19 frictionally engaging with the arm 15. 75

When the device is in use and it is desired to maintain the window sash in an elevated position, then the sleeve 18 is slid longitudinally on the outwardly disposed arm of the locking member 17, and in this 80 way the tongue 19 is disengaged from the arm 15 of the U-shaped member 13.

The locking member 17 may now be rotated until the transverse arm is angularly disposed, so that the upper edge of the arm 85 will bite into the window sash and prevent it being lowered.

The lock is then locked by sliding the sleeve 18 longitudinally on the outer arm of the locking member 17, so that the tongue 90 19 will frictionally bear upon the arm 15 of the U-shaped member 13.

This window lock is of an extremely simple nature and can be readily mounted on a window at present in use and without 95 the necessity of disassembling the window.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense. 100

105 What I claim as my invention is:

1. A window lock comprising a U-shaped member designed to be secured to a window

frame, the arms of the U-shaped member being outwardly disposed, an angle shaped locking member pivotally mounted in the U-shaped member, and means carried by the locking member for mounting the said locking member in the desired position.

2. The window lock claimed in claim 1, in which the means for maintaining the locking member in the desired position, con-

sists of a slidable sleeve provided with a tongue which frictionally bears on one arm of the U-shaped member.

In witness whereof I have hereunto set my hand in the presence of two witnesses.

CHARLES GEORGE CALLAN.
